UNITED STATES PATENT OFFICE.

JACOB H. FLEISCH, OF NEW YORK, N. Y.

DESIGN FOR A NECKTIE.

SPECIFICATION forming part of Design No. 19,760, dated April 15, 1890.

Application filed March 5, 1890. Serial No. 342,794. Term of patent 3½ years.

To all whom it may concern:

Be it known that I, JACOB H. FLEISCH, a citizen of the United States, residing at New York city, in the county of New York and State of New York, have invented and produced a new and original Design for Neckties, of which the following is a specification, reference being had to the accompanying drawings, forming a part thereof.

10 My invention relates to a novel design for neckties; and it consists in the configuration of parts thereof, substantially as illustrated in the accompanying drawing, whereby the so-called knot-piece shall have the appearance 15 of being buttoned.

The drawing represents a tie or scarf embodying the design.

The knot-piece consists of the parts A and B, the part A overlapping the part B, the 20 edges of the part A being inclined so that it extends diagonally across the part B. The part B is extended above the top of the part

A and folded over to produce a loop C. The diagonal edge of the part A is of a different shade from the remaining portion of part A, 25 so as to bring out more prominently the overlapping feature of the parts. The ends of the tie project downwardly from the lower ends of the parts A B, as shown in the drawing. A series of buttons F are secured to the part 30 A in proximity to its edge, and projecting from these buttons is a series of stitches G, arranged to represent button-holes. Thus it will be seen the knot of the tie has the appearance of being buttoned, which is the essential feature of the design. 35

What I claim is—

The design for a necktie herein shown and described.

JACOB H. FLEISCH.
